UNITED STATES PATENT OFFICE.

WILLIAM H. BAKER, OF CENTRAL FALLS, RHODE ISLAND, AND FREDERIC E. KIP, OF MONTCLAIR, NEW JERSEY.

DESIGN FOR A TERMINAL FOR ELECTRIC CIRCUITS.

SPECIFICATION forming part of Design No. 30,207, dated February 14, 1899.

Application filed November 8, 1898. Serial No. 695,894. Term of patent 14 years.

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented and produced a new, useful, and original Design for an Article of Manufacture—namely, a Terminal for Electric Circuits—of which the following is a specification, reference being had to the accompanying drawings, forming a part thereof.

In the said drawings, Figure 1 is a perspective view of our terminal, illustrating its shape; and Fig. 2 is an end view of the same.

The leading feature of our design for a terminal consists in the two metal strips of different thicknesses meeting edge to edge, the shoulders formed on the thicker strip at the said junction, and the two strips of non-metallic material differing from the metal in appearance and extending along the edge of the thicker metal strip adjacent to the thinner metal strip.

A is the thicker metal body portion or strip 25 of the terminal. B is the thinner metal strip or portion projecting from the edge of the body portion A, the lateral faces of the strips being offset at *a a*, and C is an interposing strip of non-metallic insulating material between the overlapping portions of the strips A and B, said strip C differing in appearance from the metallic strips A and B.

What we claim is—

The design for an electric-circuit terminal, 35 substantially as herein shown and described.

In witness whereof we have hereunto signed our names in the presence of two subscribing witnesses.

WILLIAM H. BAKER.
FREDERIC E. KIP.

Witnesses for William H. Baker:

FRED. M. ARMSTRONG,
CLAUDE J. FARNSWORTH.
